UNITED STATES PATENT OFFICE.

MOSES L. FOOTE AND WILLIAM M. KINGSBURY, OF CLEVELAND, OHIO.

BOILER AND FURNACE GRATE.

1,414,732.

Specification of Letters Patent. Patented May 2, 1922.

Application filed April 9, 1920. Serial No. 372,544.

To all whom it may concern:

Be it known that we, MOSES L. FOOTE and WILLIAM M. KINGSBURY, citizens of the United States, residing at Cleveland, in the 5 county of Cuyahoga and State of Ohio, have invented certain new and useful Improvements in Boiler and Furnace Grates, of which the following is a specification.

This invention relates to grates of a type 10 somewhat similar to that for which we have obtained U. S. Patent #1816725 dated September 23, 1919.

In said patent there is disclosed a water-cooled grate bar made substantially in one 15 piece with inclined passages through the same communicating with a transverse header extending across the front of the fire box.

The present invention is an improvement 20 on the grate bar referred to, the improvement consisting of various features as will more fully appear from the following description.

It may be said, however, that the present 25 grate bar is built up of pipe sections connected at the rear by a return bend casting, and connected at the front to a header, the front connection being especially simple and convenient, and including a draw plate 30 and a single bolt which connects the bar to the header, with slip nipples, permitting the connection to expand and contract at all angles. These features will receive further description below.

35 In the accompanying drawings Fig. 1 is a side elevation of the grate bar with the header and fire box wall in section. Fig. 2 is a front elevation of the header. Figs. 3 and 4 are details of one of the draw plates. 40 Figs. 5 and 6 are details of one of the front connections. Figs. 7, 8 and 9 are details of the rear end bend. Fig. 10 is a detail of the bridge between the tubes.

The grate bars are set in through an 45 elongated opening in the front wall 6 of the fire box, and are all connected to a header 7 having upper and lower circulation passages 8 and 9 with inlet and outlet connections 10 and 11 at the end for the water 50 circulation.

Each grate bar consists of an upper tube 12 and a lower tube 13 which are set at an angle to each other, or converging to the rear, where they are tapped into a return bend casting 14 which has on its rear side a lug 15 adapted to rest on a ledge 16

or other rear support. The bends have spacing lugs 17 to space the bars apart a proper distance. At the front end each of the tubes 12 and 13 extends through a hole in the 60 draw plate 18, these plates being of proper size and shape to space the bars apart and to fit and fill the opening in the front wall 6 of the fire box. Each tube is screwed into a head connection 19, on the outside of the 65 draw plate, and each connection receives one end of a tapered slip nipple 20, the other end of which fits into an opening at 21 in the rear wall of the header, and communicates with the appropriate passage therein. 70

The header has a cored opening at 22 in the partition between the passages to receive a bolt 23 which connects the header and the draw plate. The head of the bolt sets in a countersunk recess 24 in the back 75 of the draw plate, the front of which stops against the fittings 19 which rest on lugs 25 formed on the face of the draw plate, the connections being squared as shown at 26 to prevent turning thereof. The outer 80 end of the bolt receives the nut 27.

When the bolt is drawn up the slip nipples are forced into contact to make the joints between the header and the tubes, the thrust being taken by the draw plate 18 against 85 the connections 19. The use of a single bolt for making this connection permits expansion at various angles, the single bolt serving to pull both of the joints to contact with the transverse header, and the draw plates 90 form a stop-off to close the opening in the front of the fire box and to hold the bars in proper spacing. A bridge 30 is placed between the upper and lower tubes to form a support and to keep the bars in alignment. 95 The whole forms a cheap and convenient assembly for a hollow grate bar, and any grate bar can be removed or inserted by simply disconnecting the bolt and removing the nipples and connections and then lifting the 100 grate bar out through the fire box and front door of the furnace.

We claim:

1. The combination with a transverse header having passages therein, of a fire 105 box having a front opening, and a plurality of grate bars each having upper and lower tubes communicating with said passages, a draw plate between the outer ends of the tubes and fitting the opening in the fire box, 110 and a bolt between the draw plate and header.

2. The combination with a fire box having an opening in its front wall, of a plurality of tubular grate bars the outer ends of which extend through said opening, 5 separate draw plates mounted upon the bars respectively, said draw plates fitting in and closing said opening, an external header with which the grate bars communicate, and connections between the header and the re-

spective draw plates, to attach the bars to 10 the header.

In testimony whereof, we do affix our signatures in presence of two witnesses.

MOSES L. FOOTE.

WILLIAM M. KINGSBURY.
